BENZOIC ACID AMIDES SHOWING ANTIMYCOTIC ACTION AND A PROCESS FOR THEIR MANUFACTURE

Heinrich Ruschig, Bad Soden (Taunus), and Gerhard Körger, and Georg Neseemann, Frankfurt am Main, Germany, assignors to Farbwerke Hoechst Aktiengesellschaft vormals Meister Lucius & Brüning, Frankfurt am Main, Germany, a corporation of Germany

No Drawing. Application December 19, 1958
Serial No. 781,453

Claims priority, application Germany January 26, 1956

6 Claims. (Cl. 260—559)

The present invention relates to benzoic acid amides showing antimycotic action and a process for their manufacture, and it especially relates to compounds selected from the group consisting of benzoic acid amides of the general formula

wherein Hal represents a member selected from the group consisting of chlorine, bromine and iodine, R₁ is a member selected from the group consisting of alkyl and alkenyl radicals containing 2-7 carbon atoms, phenylalkyl radicals containing an alkylene group with at most 2 carbon atoms, cycloalkyl and cycloalkylalkyl radicals containing 5-8 carbon atoms, R₂ is a member selected from the group consisting of hydrogen and an alkyl group having at most 4 carbon atoms, and alkali metal salts of these compounds.

It is known that for the treatment of mycoses in human beings a large number of medicaments can be used whose active components belong to quite different substance groups. In addition to inorganic active substances, there have been recommended, for instance, phenols, such as 2,2'-dihydroxy-5,5'-dichloro-diphenyl sulphide fatty acids, dyestuffs, invert soaps, organic mercury compounds, antibiotics, quinoline derivatives, halogenated salicylic acid anilides, especially 5-bromo-salicylic acid-4'-chloranilide (cf. Deutsche Medizinische Wochenschrift, 79 (1954), page 1297).

It is further known that the calcium salt of 5-bromo-salicylic acid-isopropyl amide in admixture with sulfanilyl carbamide can be used for preparing an antiseptic vulnerary powder (cf. Zentralblatt, 1952, page 4657).

It is also known that alkyl amides, halogenated in β -position, of halogenated salicylic acids, particularly 3,5-dichloro-2-hydroxy-benzoic acid- β -chlorethyl amide can be used as preserving agent for wood or paper-pulp (compare French Patent 1,099,272).

Finally, 6-halogen-3-hydroxy-benzoates were already proposed as an antimycotic.

Now, we have found that benzoic acid amides showing a good antimycotic action and, simultaneously, a very low protein factor, are obtained by reacting, in a usual manner, reactive derivatives of 4-halogen-2-hydroxybenzoic acids with amines of the general formula

wherein R₁ is a member selected from the group consisting of alkyl and alkenyl radicals containing 2-7 carbon atoms, phenylalkyl radicals containing an alkylene

2

group with at most 2 carbon atoms, cycloalkyl and cycloalkylalkyl radicals containing 5-8 carbon atoms, R₂ is a member selected from the group consisting of hydrogen and an alkyl group having at most 4 carbon atoms.

As reactive derivatives of 4-halogen-2-hydroxy-benzoic acids there are particularly suitable their esters with low molecular aliphatic alcohols or with phenols as well as the corresponding halides and azides.

10 As halogen substituents in the benzene nucleus of the 4-halogen-2-hydroxy-benzoic acid derivatives used as starting substances according to the invention there may be used chlorine, bromine and iodine.

As amines there can be used primary or secondary 15 amines of straight-chained or branched, saturated or unsaturated aliphatic character, preferably primary amines with an aliphatic radical containing 3-6 carbon atoms.

The following compounds may be mentioned, for instance: ethylamine, n-propylamine, isopropylamine, n-20 butylamine, isobutylamine, secondary butylamine, tertiary butylamine, n-pentylamine, isoamylamine, n-hexylamine, n-heptylamine, allylamine, crotylamine, methylpropylamine and di-n-propylamine. Araliphatic amines, such as benzylamine, β -phenyl-ethylamine can also be 25 used.

As cycloalkyl- or cycloalkyl-alkylamines there can be used, for instance: Cyclo-pentylamine, cyclo-hexylamine, cycloheptylamine, cyclo-hexyl-methylamine and cyclohexyl-ethylamine.

30 According to the process of the invention the reaction conditions can be varied to a large extent. For instance, the reactions can be carried out in the presence or absence of solvents or diluents, at low or at elevated temperatures, temperatures in the range from 70° C. to

35 100° C. having proved to be favourable for the reactions of the 4-halogen-2-hydroxy-benzoates with amines. Temperatures below +10° C. are chosen when 4-halogen-2-hydroxy-benzoic acid azides are used. The amines can be used in an equimolar amount or in excess.

40 Together with amines the products obtained according to the process of the invention form complex compounds which contain one mol of amine per each two mols of amide.

The products obtained according to the process of the 45 invention are valuable medicaments and are, in particular, appropriate to be administered as antimycotics. As such, in addition to very good tolerability, they are of considerable action and are especially characterized by a very low protein factor, whereby the partial or complete 50 inactivation of antimycotic substances in the presence of protein is to be understood.

The antimycotic action of various products obtained according to the process of the invention on a large number of fungi pathogenic to humans, with or without addition of protein, are to be seen from Tables I and II.

55 The concentrations indicated in γ /ml. in the tables were sufficient enough as to completely inhibit, in a solid culture medium, any growth of the fungi mentioned above, even after a period of 18 days. The relative protein factors indicated constitute a ratio for the relative 60 inactivation of the products claimed according to the invention by addition of serum and indicate the multiple by which the antimycotic action is reduced in the presence of protein.

65 The benzoic acid amides obtained according to the process of the invention and containing in the benzene nucleus bromine or iodine show the same action against fungi pathogenic to humans as the chlorine compounds mentioned in the tables, irrespective of serum being added or not.

In contradistinction to comparable compounds showing antimycotic action which are hitherto known, the

products obtained according to the process of the present invention are characterized by a better activity, especially in the presence of protein, and by a low protein factor hitherto nearly unknown. Generally, the protein factor of the known compounds showing antimycotic action amounts to more than 30 and was found to be in the range of 32 to 120 for the known 5-bromo-salicylic acid-4'-chloro-anilide, when examined under comparable conditions and with various fungi.

therapeutical treatment were favourably influenced by a solution of 2% strength of, for instance, 4-chloro-2-hydroxy-benzoic acid-n-butylamide.

Clinical tests also confirmed the good tolerability of the products obtained according to the process of the invention. Soon after the treatment with the benzoic acid amides obtained according to the process of the invention has been started, the disagreeable pruritus disappears. The good nonirritant tolerability of the prod-

The benzoic acid amides obtainable according to the process of the present invention are very non-toxic substances. For instance, 4-chloro-2-hydroxy-benzoic acid-n-butylamide obtained according to the process of the present invention is tolerated in Swiss mice in doses up to 10 grams/kilogram in a suspension of 10% strength in starch mucilage. Also as regards the subchronic toxicity, the products of the process claimed are favourably judged as the test described by the following has shown. A large number of male Swiss mice having a weight of 100 to 150 grams was fed 28 times within 38 days with a dose of 1 gram/kilogram each time of 4-chloro-2-hydroxy-benzoic acid-n-butylamide. All animals showed a normal behaviour and an increase in weight. After autopsy no visible pathological alteration was observed. The histological examination of the organs did not disclose any alteration which could be attributed to a damage caused by the product claimed according to the process of the invention. The compounds obtained according to the process of the invention are also well tolerated by the mucous membrane. When tested intracutaneously or epicutaneously in the rabbit's ear, a solution of 10% strength of 4-chloro-2-hydroxy-benzoic acid-n-butyl-amide did not cause any irritation. Also in the rabbit's eye the solution was tolerated without causing irritation.

Clinical tests fully confirmed the antimycotic action of the products obtained according to the process of the invention, for instance of 4-chloro-2-hydroxy-benzoic acid-n-butylamide. Even in cases resistant to therapeutical treatment, for instance hyperkeratotic, obstinate interdigital-mycoses, scrotal mycoses, anal mycoses as well as in cases showing thrush (soor) character, very good results could be obtained. Also chronic epidermophytoses existing for a long time and, hitherto, resistant to all

products obtained according to the process of the invention is of particular importance when treating anal mycosis.

The new products can be administered in substance as well as in solution or emulsion, furthermore in the form of ointments or powders if desired in admixture with one another and/or with other compounds showing an antimycotic or bactericidal action. The products of the invention can also be used in the form of their salts or in the presence of substances which lead to the formation of their salts. For the salt formation alkaline agents, such as alkali metal hydroxides or alkaline earth metal hydroxides, furthermore physiologically tolerable organic bases can be used. Alkali metal salts are particularly appropriate since they are characterized by a very good resistance to the air.

The following examples serve to illustrate the invention, but they are not intended to limit it thereto:

Example 1.—4-chloro-2-hydroxy-benzoic acid-n-butyl-amide

A mixture consisting of 114 grams of 4-chloro-2-hydroxy-benzoic acid-n-butyl-ester, 64 grams of methanol and 130 grams of n-butyl-amine is heated for 22 hours at 80° C.; then the parts volatile up to 130° C. are distilled off under reduced pressure. The residue crystallizing in the cold is dissolved in 200 cc. of methanol and the solution obtained is slowly added dropwise and while stirring into dilute hydrochloric acid, if necessary, after treatment with animal charcoal. The precipitate which is at first semi-solid soon crystallizes completely. It is filtered with suction, washed with dilute hydrochloric acid, then thoroughly washed again with water, and the product obtained in good yield is dried in the air. After having been recrystallized twice from

carbon tetrachloride the 4-chloro-2-hydroxy-benzoic acid-n-butylamide melts at 90-92° C.

Together with amines and in the same manner as the amides described below the 4-chloro-2-hydroxy-benzoic acid-n-butylamide forms complex compounds which per 2 molecules of amide contain 1 molecule of amine. The complex compound of 2 molecules of 4-chloro-2-hydroxy-benzoic acid-n-butylamide and 1 molecule of n-butylamine after recrystallization from chloroform melts at 98-100° C.

Sodium salt of 4-chloro-2-hydroxy-benzoic acid-n-butylamide

68.3 grams of 4-chloro-2-hydroxy-benzoic acid-n-butylamide are dissolved in 300 cc. of 1 N-sodium hydroxide solution, while being warmed. On cooling, the sodium salt crystallizes as hydrate and in the form of white crystals. It is vigorously filtered with suction, the product obtained is dissolved, while heated, in 200 cc. of acetone, the pH is adjusted to about 8 by dropwise adding concentrated sulphuric acid, the mixture is filtered and ether is slowly added to the acetic solution. Thereby the sodium salt of 4-chloro-2-hydroxy-benzoic acid-n-butylamide precipitates in the form of snow white crystals as trihydrate. The anhydrous salt shows a melting point of 275-280° C. (with decomposition).

Example 2.—4-chloro-2 - hydroxy-benzoic acid-n-hexylamide

18.6 grams of 4-chloro-2-hydroxy-benzoic acid-methyl-ester, 13 grams of methanol and 40 grams of n-hexylamine are reacted and worked up as described in Example 1. After having been recrystallized twice from cyclohexane 4-chloro-2-hydroxy-benzoic acid-n-hexyl-amide is obtained in a good yield. The product melts at 75-76.5° C.

In an analogous manner the following amides were prepared:

- 4-chloro-2-hydroxy-benzoic acid-isobutyl-amide melting at 116-117° C. (after recrystallization from carbon tetrachloride)
- 4-chloro-2-hydroxy-benzoic acid-n-propyl-amide melting at 80-82.5° C. (after recrystallization from cyclohexane)
- 4-chloro-2-hydroxy-benzoic acid-iso-propyl-amide melting at 92-94° C. (after recrystallization from cyclohexane)
- 4-chloro-2-hydroxy-benzoic acid-n-pentyl-amide melting at 68-69° C. (after recrystallization from diiso-propyl-ether)
- 4-chloro-2-hydroxy-benzoic acid-benzyl-amide melting at about 123-127° C. (after recrystallization from diiso-propyl-ether)
- 4-chloro-2-hydroxy-benzoic acid-isoamyl-amide melting at 108-110° C. (after recrystallization from cyclohexane).

Example 3.—4-chloro-2-hydroxy-benzoic acid-allyl-amide

20 grams of 4-chloro-2-hydroxy-benzoic acid-ethyl-ester, 18 grams of ethanol and 5.8 grams of allylamine are heated for 20 hours at 100° C. The reaction mixture obtained is cooled and introduced dropwise, while stirring, into 0.1 N-hydrochloric acid. The crystallized precipitate is filtered off with suction, dissolved in 50 cc. of methanol, the solution is treated twice with charcoal in order to be decolorized, the amide is again precipitated by introduction into 0.1 N-hydrochloric acid and dried at the air. After recrystallization from diiso-amyl-ether the 4-chloro-2-hydroxy-benzoic acid-allyl-amide melts at 91-93° C.

Example 4.—4-chloro-2-hydroxy-benzoic acid-β-phenyl-ethyl-amide

Starting from 18.6 grams of 4-chloro-2-hydroxy-benzoic acid-methylester, 18 grams of ethanol and 12 grams

of β-phenyl-ethyl-amine the 4-chloro-2-hydroxy-benzoic acid-β-phenyl-ethyl-amide is prepared according to the description given in Example 3. After having been recrystallized twice from carbon tetrachloride the amide melts at 95-99° C.

Example 5.—4-chloro-2 - hydroxy - benzoic acid-n-butyl-amide

34 grams of 4-chloro-2-hydroxy-benzoic acid, 51 grams 10 of freshly distilled oxalyl chloride and 100 cc. of absolute benzene are heated for 5 hours to boiling, while stirring, whereby slow decomposition of the acid sets in together with evolution of gaseous hydrogen chloride. The solution is boiled for 3 further hours and then distilled under 15 reduced pressure so that the parts volatile up to 50° C. are removed as completely as possible. The residue which 20 completely crystallizes on cooling and after having been pressed on clay melts at about 150° C. constitutes as crude product the 4-chloro-2-hydroxy-benzoic acid chloride and is reacted without having been purified again. It is dissolved in 120 cc. of absolute benzene. A solution of 33 grams of n-butylamine in 30 cc. of benzene 25 is added dropwise within 30 minutes to this solution, while stirring and cooling it with ice. Then it is heated for 2 hours at 50-60° C., cooled, and to the resulting reaction mixture 1 litre of petroleum ether is slowly added. Thereby a crystalline precipitate is separated which is filtered with suction and well dried. The finely pulverized product is triturated in several portions with 30 water, dilute hydrochloric acid and again with water, then filtered off with suction and dried in the air. After having been recrystallized twice from carbon tetrachloride the 4-chloro-2-hydroxy-benzoic acid-n-butyl-amide is obtained in the form of white leaflets melting at 90-92° C.

Example 6.—4-bromo-2 - hydroxy-benzoic acid-n-butyl-amide

23 grams of 4-bromo-2-hydroxy-benzoic acid-ethyl-ester (prepared by esterification of 4-bromo-2-hydroxybenzoic acid of a melting point of 214-215° C. with 40 ethanol in the presence of concentrated sulphuric acid), 14.6 grams of n-butylamine and 16 cc. of ethanol are heated for 20 hours at 80° C. The cooled reaction mixture is introduced, while stirring, into dilute hydrochloric acid, and the crystalline precipitate is filtered off with suction. Then the precipitate is washed with water, triturated in several portions by means of dilute hydrochloric acid and filtered sodium bicarbonate solution, and then the 4-bromo-2-hydroxy-benzoic acid-n-butylamide obtained in a very good yield and already in a very pure 45 state is dried at the air (melting point 105-106.5° C.). After recrystallization from cyclohexane the melting point is within the range of 106.5-107° C.

Example 7.—4-iodo-2-hydroxy-benzoic acid-n-butyl-amide

11 grams of 4-iodo-2-hydroxy-benzoic acid hydrazide melting at 186-188° C. (prepared by reaction of 4-iodo-2-hydroxy-benzoic acid methylester and hydrazine hydrate in methanol) are suspended in 15 cc. of glacial acetic acid and 230 cc. of 2 N-hydrochloric acid and diazotised, while cooled and stirred, with a solution of 5.7 grams of sodium nitrite in 20 cc. of water. The whole is again stirred for 15 minutes and the mixture is thoroughly shaken with ice-cooled ether. The ethereal solution is still shaken five times with ice-water and twice with sodium bicarbonate solution and dried for 15 minutes over sodium sulphate. The dry ethereal solution of the 4-iodo-2-hydroxy-benzoic acid azide is added to 60 an ethereal solution of 5.8 grams of n-butyl-amine and the reaction mixture is allowed to stand for 24 hours at 0° C. The desired 4-iodo-2-hydroxy-benzoic acid-n-butyl-amide is obtained, which, after having been recrystallized twice from carbon tetrachloride melts at 107.5-110° C.

Example 8.—4-chloro-2-hydroxy-benzoic acid-(N-ethyl-N-allyl)-amide

As described in Example 7, 19.6 grams of 4-chloro-2-hydroxy-benzoic acid hydrazide are diazotised in water with a solution of 7.3 grams of sodium nitrite, and the 4-chloro-2-hydroxy-benzoic acid azide obtained is reacted in an ethereal solution with 17 grams of allyl-ethyl-amine. After having been correspondingly worked up, and recrystallized from cyclohexane, the 4-chloro-2-hydroxy-benzoic acid-(N-ethyl-N-allyl)-amide, melting at 93-95° C., is obtained.

Example 9.—4-chloro-2-hydroxy-benzoic acid-cyclohexyl-amide

18.6 grams of 4-chloro-2-hydroxy-benzoic acid methyl-ester, 40 grams of cyclohexylamine and 20 cc. of methanol are heated for 24 hours at about 100° C. The cooled reaction mixture is introduced, while stirring, into 300 cc. of 1 N-hydrochloric acid. After having been allowed to stand for a short time the semi-solid precipitate crystallizes. The precipitate is filtered with suction, washed with water, the crystals are triturated with 2 N-hydrochloric acid, again filtered off with suction and washed again with water. After drying, 23 to 24 grams of 4-chloro-2-hydroxy-benzoic acid-cyclohexyl-amide (90-94% of the theoretical yield) are obtained, which is already very pure and melts at 126-128° C. After recrystallization from cyclohexane it melts at 129-131° C.

When using cyclopentylamine the 4-chloro-2-hydroxy-benzoic acid-cyclopentyl-amide melting at 107-108.5° C. is obtained in an analogous manner.

Example 10.—4-chloro-2-hydroxy-benzoic acid-cyclo-hexyl-methyl-amide

19.6 grams of 4-chloro-2-hydroxy-benzoic acid-hydrazide melting at 207-210° C. (prepared by reaction of 4-chloro-2-hydroxy-benzoic acid methylester with hydrazine hydrate in methanol) are suspended in 125 cc. of glacial acetic acid and 400 cc. of 2 N-hydrochloric acid. The mixture is cooled to about -3° C. and diazotised, while stirring, with a solution of 7.3 grams of sodium nitrite in 50 cc. of water. It is again stirred for 10-15 minutes and then the mixture is shaken with about 800 cc. of ice-cooled ether. The ethereal solution of the 4-chloro-2-hydroxy-benzoic acid azide is shaken in several portions five times with ice water and twice with sodium bicarbonate solution and dried for 15 minutes over sodium sulphate. A solution of 22.6 grams of cyclohexyl-methyl-amine in 15 cc. of absolute ether is added while cooling and shaking to the dry ether solution. The mixture is allowed to stand for 24 hours at 0° C., then the ether is distilled off, finally under reduced pressure. The crystalline residue is triturated in a mortar with 2 N-hydrochloric acid, the precipitate is filtered off with suction and washed with water. It is then triturated with a filtered sodium bicarbonate solution, again filtered with suction, washed with water and dried. The 4-chloro-2-hydroxy-benzoic acid-cyclo-hexyl-methyl-amide obtained in a good yield melts at 109-110° C. after having been recrystallized from cyclohexane.

Example 11.—4-chloro-2-hydroxy-benzoic acid-n-heptyl-amide

75 grams of 4-chloro-2-hydroxy-benzoic acid-hydrazide are suspended in 150 cc. of glacial acetic acid and 1000 cc. of 2 N-hydrochloric acid. The mixture is cooled to 0° C. and diazotized, while stirring, with a solution of 27.6 grams of sodium nitrite in 50 cc. of water. It is again stirred for 15 minutes and then the mixture is shaken with about 1600 cc. of ice-cooled ether. The ethereal solution of the 4-chloro-2-hydroxy-benzoic acid-azide is shaken at first with ice water and then with sodium bicarbonate solution and, after drying over sodium sulfate, 69 grams of n-heptyl-amine are added in portions. The ethereal solution is allowed to stand for 24

hours and is then shaken successively with dilute hydrochloric acid and sodium bicarbonate solution. The 4-chloro-2-hydroxy-benzoic acid-n-heptyl-amide that has formed is removed from the ethereal solution by means of dilute sodium hydroxide solution. The alkaline solution so obtained is clarified with charcoal, acidified with hydrochloric acid, the precipitate is sucked off and recrystallized from about 5 liters of methanol of 80% strength. The 4-chloro-2-hydroxy-benzoic acid-n-heptyl-amide so obtained melts at 66-67° C.

In an analogous manner there are obtained: from 4-chloro-2-hydroxy-benzoic acid-azide and ethyl amine the 4-chloro-2-hydroxy-benzoic acid-ethyl amide, melting point 97-98° C. (from methanol of 60% strength); from 4-chloro-2-hydroxy-benzoic acid azide and crotyl amine the 4-chloro-2-hydroxy-benzoic acid-crotyl amide, melting point 113-115° C. (from methanol of 80% strength); from 4-chloro-2-hydroxy-benzoic acid-azide and diethyl amine the 4-chloro-2-hydroxy-benzoic acid-diethyl amide, melting point 126-128° C. (from methanol of 60% strength).

This application is a continuation-in-part of application Serial No. 635,109, filed January 22, 1957, now abandoned.

25 We claim:

1. Compounds selected from the group consisting of benzoic acid-amides of the general formula

wherein Hal represents a member selected from the group consisting of chlorine, bromine and iodine, R₁ is a member selected from the group consisting of alkyl, alkenyl radicals containing 2-7 carbon atoms, phenyl-alkyl radicals containing an alkylene group with at most 2 carbon atoms, cycloalkyl and cycloalkylalkyl radicals containing 5-8 carbon atoms, R₂ is a member selected from the group consisting of hydrogen and an alkyl group having at most 4 carbon atoms, and alkali metal salts of these compounds.

2. The compound of the formula

3. The compound of the formula

4. The compound of the formula

5. The compound of the formula

6. The compound of the formula
